UNITED STATES PATENT OFFICE.

WILLIAM J. ADAM, OF NORWOOD, MASSACHUSETTS, ASSIGNOR TO THE PLIMPTON PRESS, OF NORWOOD, MASSACHUSETTS, A CORPORATION OF MASSACHUSETTS.

INK-SUPPLY FOR PRINTING-PRESSES.

1,112,412.

Specification of Letters Patent. Patented Sept. 29, 1914.

Application filed July 16, 1914. Serial No. 851,276.

To all whom it may concern:

Be it known that I, WILLIAM J. ADAM, a citizen of the United States, residing at Norwood, in the county of Norfolk and State of Massachusetts, have invented new and useful Improvements in Ink-Supplies for Printing-Presses, of which the following is a specification, reference being had to the accompanying drawings, forming part 10 thereof.

This invention has reference to improvements in adjusting means for adjusting the delivery of ink to the ink roller of an ink supply device for printing machines.

15 The object of the invention is to so construct an adjusting means for the knife of a printing press ink supply device that change of adjustment of any or all adjusting screws may be facilitated.

20 Other objects of the invention will appear from the following description.

The invention consists in the scale and in the series of screws for adjusting the knife together with the collars on said screws 25 which collars can be loosened from their screws and rotated relative to the graduations on the scale and then again secured to their adjusting screws.

20 The invention also consists in such other novel features of construction and combination of parts as shall hereinafter be more fully described and pointed out in the claim.

Figure 1, represents a sectional view of the improved ink supply adjusting device as 35 taken on line 1-1 Fig. 2. Fig. 2, represents a view of the same in elevation looking from a point at the right hand side of Fig. 1.

Similar characters of reference designate 40 corresponding parts throughout.

45 As shown in the drawings 5 represents the usual angle beam which extends transversely of the printing press and has the inclined member 6 carrying the spacer 7 on which the usual knife 8 is secured by screws as 9. The roll 10 is the usual ink supply roll which is mounted to rotate past the lower edge 8' of the knife 8, the thickness of the layer of ink taken by the periphery of this roll 10 being determined by the spacing 50 of such edge 8' from the roll 10 and such spacing being accomplished by flexing the knife 8 more or less from the screws as 9.

55 The member 6 of beam 5 has a series of screw threaded perforations arranged in alinement along said member on a line

which is parallel with the edge 8' of the knife 8 and in all of said screw threaded perforations are arranged the adjusting screws 11-11 having the thumb pieces 12-12 and the ends 13 which latter bear against the under side of the knife along a line intermediate the spacer 7 and the edge 8' of knife 8. On the shank of each of the adjusting screws 11, 11 is rotatably mounted the collar 14 having the set screw 15 and the peripheries of 60 said collars are graduated as shown in the drawings. Mounted on the beam 5 is the scale member 16 having the edge 16' which overlaps the edges of the collars 14, 14, as 65 shown in Fig. 1 of the drawings and has the series of graduations indicated in Fig. 2 of the drawings by the characters *o*, *o* on said scale member, which graduations are parallel with the axes of the adjusting screws 11, 11.

70 In the operation of this device ink is placed on the upper surface of knife 8 and flows against the periphery of the ink roll 10 so that if said roll is rotated in the direction indicated by its arrow the film or ink carried forward by said ink roll will be determined by the space between the edge 8' of 75 said knife 8 and the periphery of said roll 10. The screws 11, 11 are now adjusted by turning their thumb pieces 12, 12 and the 80 knife 8 is flexed away from the surface of the spacer 7 until the entire length of edge 8' of knife 8 is brought to a position relative to the periphery of roll 10 to permit the flow between said edge 8' and said roll of an arbitrarily determined normal amount of ink.

If after such adjustment of the screws 11, 11 the graduations of collars 14, 14 thereof be compared with the graduations of scale member 16 it will usually be found that the 85 graduations on the collars 14, 14 in registry with the graduations *o*, *o* on said scale member do not agree as to their indicating characters and hence in further adjustment of 90 said screws or any of them would require that a record of such variations be first taken so that the degree of the various adjustment of said screws 11, 11 could be made accurately. To obviate the taking of such record and to simplify future accurate adjustment 95 of said screws I now loosen the set screws 15, 15 of any of such collars as need adjustment and rotate said collars on their screws until the *o* graduation on each of said collars 14 is in registry with the related *o* grad- 100 105 110

uation on the scale member 16. Thereafter the screws 11, 11 or any of them can be accurately adjusted by rotating said screw or screws forward or backward relative to the 5 graduations on the scale member 16 and all of said screws 11, 11 can be readily brought to the predetermined normal position.

Having thus described my invention I claim as new and desire to secure by Letters 10 Patent.

An ink supply for printing presses comprising a beam having an inclined member furnished with a series of screw threaded 15 perforations arranged in line, a spacer carried by said member, a knife carried by said

spacer and adapted to be flexed, a scale depending from said beam member and having graduations extending parallel with the axes of said perforations, a series of adjusting screws received by said perforations and 20 having ends bearing against said knife, and a series of collars rotatable on said adjusting screws and having peripheral graduations and set screws whereby said collars can be secured in adjusted position on said 25 adjusting screws.

WILLIAM J. ADAM.
